CLAIM

The ornamental design for a vaporizing cartridge, as shown and described.

DESCRIPTION

FIG. 1 is a front isometric view of a first embodiment of a vaporizing cartridge embodying the new design;

FIG. 2 is a front view of the design shown in FIG. 1;

FIG. 3 is a rear view of the design shown in FIG. 1;

FIG. 4 is a top view of the design shown in FIG. 1;

FIG. 5 is a bottom view of the design shown in FIG. 1;

FIG. 6 is a right side view of the design shown in FIG. 1;

FIG. 7 is a left side view of the design shown in FIGS. 1; and

FIG. 8 is a cross-section view taken along **8-8** in FIG. 4 of the design shown in FIG. 1.

FIG. 9 is a front isometric view of a second embodiment of a vaporizing cartridge embodying the new design;

FIG. 10 is a front view of the design shown in FIG. 9;

FIG. 11 is a rear view of the design shown in FIG. 9;

FIG. 12 is a top view of the design shown in FIG. 9;

FIG. 13 is a bottom view of the design shown in FIG. 9;

FIG. 14 is a right side view of the design shown in FIG. 9;

FIG. 15 is a left side view of the design shown in FIGS. 9; and,

FIG. 16 is a cross-section view taken along **16-16** in FIG. 12 of the design shown in FIG. 9.

The broken lines in the drawings depict portions of the vaporizing cartridge that form no part of the claimed design.

1 Claim, 14 Drawing Sheets
